DUCT SUPPORTED HUMIDIFIER

Robert F. Fraser, Livingston, N.J., assignor to Walton Laboratories, Inc., Union, N.J., a corporation of New Jersey

Filed Nov. 26, 1965, Ser. No. 88,237

Term of patent 14 years

(Cl. D62—4)

FIG. 1

FIG. 2

FIG. 3

FIG. 4

FIG. 5

FIG. 6

FIG. 1 is a side elevational view of a duct supported humidifier showing my new design;

FIG. 2 is a bottom view thereof;

FIG. 3 is a top view thereof;

FIG. 4 is an elevational view taken from the side opposite that shown in FIG. 1;

FIG. 5 is an end elevational view thereof; and

FIG. 6 is an elevational view taken from the end opposite the end shown in FIG. 5.

I claim:

The ornamental design for a duct supported humidifier, substantially as shown.
